UNITED STATES PATENT OFFICE.

ELBRIDGE FOSTER, OF HARTFORD, CONNECTICUT.

IMPROVEMENT IN COVERS FOR TRAVELING-TRUNKS.

Specification forming part of Letters Patent No. **23,562**, dated April 12, 1859.

To all whom it may concern:

Be it known that I, ELBRIDGE FOSTER, of the city of Hartford, county of Hartford, and State of Connecticut, have invented new and useful Improvements in the Mode of Constructing Covers for Traveling-Trunks and other Articles; and I do hereby declare that the following is a correct description thereof, reference being had to the accompanying drawings, and to the letters of reference marked thereon.

The nature of my invention consists in the formation of covers or cases to protect traveling-trunks and packages from injury while traveling, and in case of accident to save them from sinking in the water.

To enable others skilled in the art to make and use my invention, I will proceed to describe its construction and operation.

In the drawings, Figure 1 is a view of the cover when not in use; Fig. 2, a view when fastened on a trunk; Fig. 3, an end view when in use, open; Fig. 4, a transverse section; Fig. 5, a plan view of bottom when extended, and Fig. 6 the case when folded up, (end view.)

In the formation of my case or cover I do not confine myself to any particular shape or size of the inflated or other parts, or the method of attaching the same to a trunk or bale of goods, &c., because the shape of the articles requiring the covers are various. I call it a "cover and life-preserved" for this reason: It can equally as well be applied to a traveling-trunk, mail-bag, bale of goods, or other article where there is a risk in traveling or transportation by water.

The main part or groundwork of my cover is composed of such description of material as usually employed in the common traveling-trunk covers. The sides A are made with a light thin iron frame of the size of the face of the trunk, and are covered on each side with cloth or duck, and with loose parts at the bottom and each end to form the covers of the ends and bottom. At the bottom edge of the frame A, I attach two or more straps B, with buckles to fasten the two sides on the trunk-bottom, also on the edges of the

frame A. On the loose parts C, I attach straps and buckles to fasten the ends together on the trunk ends. The straps D are fastened to the lower edge of the frame A and pass over the top of the trunk and buckled together when the trunk is simply used for traveling; and when the time comes for using the elastic inflated chambers E these straps are buckled tightly, as shown in Figs. 3 and 4, to draw up and extend to support the sides A of the angular air-chambers E when the article is to be used as a floating preserver, bearing in mind that the straps C are first unbuckled to allow the sides to rise up to a horizontal position at Figs. 3 and 4.

The part F that forms the angular part of the air-inflated chambers E is composed of india-rubber cloth or any other water-proof elastic and suitable material, one edge being fastened to the lower edge of the frames A and to the bottom edge of the inner sides, and all the inner surface covered with the same material, if required. When not in use the whole is folded up, as in Fig. 6, the loose parts being tucked in, so that the whole concern will not occupy much more space than a common trunk-cover.

The air-chambers E are prepared for use without disturbing the trunk internally simply by unbuckling the different straps at the ends and raising up the sides to form the angular air-chambers, the valves H being opened to admit the air and then closed to retain it. The valves must also be opened when required to discharge the air.

This article is economical in construction, and the uses it can be put to are various—viz., trunks, mails, bales of goods, &c.

What I claim as my invention, and desire to secure by Letters Patent, is—

The air-inflated trunk-cover, in the manner substantially as herein set forth, and for the purpose described, as a new article of manufacture.

ELBRIDGE FOSTER.
